UNITED STATES PATENT OFFICE.

JOHN A. McGREW AND JAMES T. LOREE, OF ALBANY, NEW YORK.

ENTRAINMENT MECHANISM FOR POWER-GENERATING UNITS.

Application filed December 29, 1921. Serial No. 525,746.

To all whom it may concern:

Be it known that we, JOHN A. McGREW and JAMES T. LOREE, both citizens of the United States, and residents of the city of Albany, county of Albany, and State of New York, have invented certain new and useful Improvements in Entrainment Mechanism for Power-Generating Units, of which the following is a specification.

10 This invention relates to entrainment mechanism for power generating units. Generically considered, our present improvement comprehends the provision of means whereby the entrainment of a power generating unit with a shaft to be driven thereby may be synchronized with the effective operation of said unit. In attaining this result, we propose to utilize the energizing medium for the power unit for the purpose of effecting a governed control of the shiftable element of the entrainment gearing, to the end that the possible stripping or mutilation of the gear teeth will be obviated.

While the invention to be hereinafter disclosed in detail is of more or less general application, it has been found particularly efficient in practice for use in connection with vehicle propulsion units and more particularly for the entrainment of an auxiliary or booster motor with a wheel axle as an aid to the main locomotive engine in accelerating the propulsion of a train from terminals or over controlling road gradients.

In a specific embodiment of our invention, 35 we provide a shiftable power transmission gear between the gear on a driving shaft actuated by the power generating unit and a gear fixed to the driven shaft. In the steam supply line for the power unit a valve 40 is interposed, the movable element of said valve being operatively connected to the bearing for the transmission gear. This valve is of such construction that in the movement of the valve element under the 45 pressure influence of the steam, the operation of the power generating unit is initiated at low speed so as to rotate the transmission gear slowly until its teeth are in proper position for full entrainment with 50 the teeth of the gear on the driven shaft. Simultaneously with such full entrainment

of the gears, the power unit is actuated at maximum speed.

Generally, our invention has for its object to provide such an entrainment mechanism 55 which is automatically actuated when the supply of the energizing medium to the power unit is established and which consists of relatively few elements of simple form, positive and reliable in their operation and 60 not likely to get out of order.

With the above and other objects in view, the invention consists in the improved entrainment mechanism and in the form, construction and relative arrangement of its 65 several parts, as will hereinafter be more fully described, illustrated in the accompanying drawings, and subsequently incorporated in the subjoined claims.

In the drawings, wherein we have disclosed an embodiment of our present invention which has given highly satisfactory results in service, and in which similar reference characters designate corresponding parts throughout the several views,

70 Figure 1 is a top plan view showing our present improvement as applied to a booster or auxiliary propulsion unit for a locomotive, its tender, coach or other wheeled vehicle;

75 Figure 2 is a detail sectional view taken on the line 2—2 of Fig. 1 showing the power transmission gear in its normal position in full lines and in an intermediate position of its entrainment movement in dotted lines; 80 and

Figure 3 is a similar view showing the full entrainment of the transmission gear with the gear on the driven shaft.

In the accompanying illustration of our 90 invention, we have shown the same as applied for use in connection with a booster or auxiliary propulsion motor such as that shown and described in our patent granted April 11, 1922, No. 1,412,250.

95 For the purposes of this explanation, it will suffice to state that the parts of the power generating unit are carried by a frame 5 which is supported in suspended relation between the spaced shaftes or axles 6 and 100 7 respectively of the vehicle truck. However, it will be manifest, as the description

- proceeds, that in so far as the novel features of this invention are concerned they are not necessarily limited in their application and use to a booster motor for vehicle trucks, 5 as the entrainment mechanism might likewise be effectively utilized for the transmission of power from power generating units of general application and use to a driven shaft. In the present disclosure we 10 have illustrated the power generating unit as including the spaced cylinders 8 in which reciprocating pistons are arranged, said pistons being connected by the driving rods 9 to opposite ends of a driving shaft 10. 15 Power is transmitted from the shaft 10 to the shaft or axle 6 by means of suitable gearing which is normally ineffective. This gearing includes a driving gear 11 fixed on the shaft 10 and a gear 12 fixed upon the 20 driven shaft 6. These gears are of such relative diameters that they do not mesh with each other and rotation is transmitted from the driving gear 11 to the gear 12 through the medium of the transmission 25 gear element 13. The latter gear is journaled in a yoke shaped frame 14 which has an oscillating bearing 15 upon the driving shaft 10 at each side of the gear 11. The frame 14 is also 30 provided with a laterally projecting bifurcated arm or fork 16, the purpose of which will be presently explained. It will be noted that the transmission gear 13 is in constant 35 meshing engagement with the teeth of the driving gear 11 and tracks around said driving gear in the rocking or oscillating movement of the bearing frame 14.
- Steam or other suitable energizing medium is supplied to the cylinders of the power 40 generating unit through the pipe 17, one end of said pipe being connected to the intake 18 which extends laterally in one direction from the lower end of a cylindrical valve casing 19. To the outlet 20 extending 45 in the opposite direction from said valve casing the pipe 21 leading to the cylinders 8 is suitably coupled or connected. The opposite sides of the wall of the valve casing 19 at its lower end are grooved or channeled 50 as at 22, the lower sides of said channels as they approach the outlet port 23 being widened or flared. The passage of the steam through the outlet port 23 is controlled by a valve piston 24 having a stem or rod 25 55 operatively connected at its upper end to the arm or fork 16 of the transmission gear frame 14. The valve piston 24 is urged downwardly to its normal position, seen in Fig. 2 of the drawings, by means of a suitable spring 26 in which position of the valve piston communication between the inlet and outlet sides of the valve cylinder is cut off and the transmission gear 13 is yieldingly 60 retained in a position in spaced relation to

the gear 12 on the driven axle, as seen in full 65 lines in said figure.

While we have described a particular form of the automatic control valve, for the movable transmission gear of the entrainment mechanism, the novel features of this valve 70 per se are not herein claimed, but are more fully described and claimed in a separate copending application for patent.

When the steam or other energizing medium for the power unit is admitted to the 75 pipe 17, it first acts against the valve piston 24, forcing said piston upwardly. When the piston reaches the position shown in dotted lines in Fig. 2, where its lower face is in a plane slightly above the lower edge 80 of the outlet port 23, the steam in relatively small volume passes through said port and the pipe 21 into the cylinders 8, so that the reciprocation of the piston is initiated at slow speed. In the movement of the valve 85 piston to such position, the frame 14 is, of course, rocked on the driving shaft 10 and the transmission gear element 13 is moved to the position shown in dotted lines in Fig. 2 of the drawing, wherein the teeth of said 90 gear element are substantially located on the peripheral line of the teeth of the gear 12. In the initial slow reciprocation of the pistons in the cylinders 8, the transmission gear 13 is, of course, rotated through the medium 95 of the gear 11 on the driving shaft 10. Instantaneously upon the registration of the teeth of the transmission gear 13 with the spaces between the teeth on gear 12, the movement of the valve piston 24 is continued 100 under the pressure influence of the steam and full entrainment of the gear element 13 with the gear 12 on the driven shaft is obtained.

In substantial concurrence with such full 105 entrainment, the steam in full volume enters the cylinders 8, so that the power generating unit is operated at its maximum speed. The valve piston 24 is now in the position seen in Fig. 3 of the drawings, the steam 110 pressure acting continuously against said valve piston to retain the transmission gear element 13 in its fully entrained position.

It will thus be apparent that, by reason of the automatically governed control of 115 the entraining movement of the transmission gear and the synchronizing of such entrainment with the effective full speed operation of the power generating unit, the possibility of stripping or mutilating the 120 gear teeth is effectively obviated.

In the use of compressed air or other means independently of the energizing medium for the power unit, for the purpose of effecting entrainment with the driven 125 axle, the breakage or mutilation of the gear teeth is not an infrequent concurrence. It will also be seen that, by reason of the

fact that we utilize the steam or other energizing medium for the purpose of automatically effecting entrainment when the operation of the power unit is initiated, instantaneously upon the cutting off of the supply of the energizing medium, the disentrainment of the power unit from the driven shaft or axle is automatically effected.

In this application, we disclose an entrainment mechanism, whereby the driven shaft or axle may be rotated in only one direction. However, in another copending application for patent, we describe and claim an entrainment gearing whereby the driven shaft or axle may be rotated in either direction, such reversible entrainment mechanism being likewise automatically governed or controlled by the steam or energizing medium for the power unit.

From the above description, considered in connection with the accompanying drawings, the construction, manner of operation, and several advantages of our present invention will be clearly understood. The entrainment mechanism consists of relatively few elements which are of simple and durable construction, so that the reliable and efficient operation thereof under various conditions of usage is assured. Furthermore, by eliminating the necessity of providing separate control valves or other means for effecting the entrainment and disentrainment of the power unit, the expense incident to the installation and maintenance of such mechanisms is reduced to a minimum.

As hereinbefore stated, the device forming the subject-matter of this application is one or more or less general application and in the great number of possible adaptations thereof it is not to be expected that certain mechanical variations in structure will not be required. It is, therefore, to be understood that while we have specifically referred to a simple and practical embodiment of the invention, it may, nevertheless, be exemplified in numerous alternative structures. Accordingly, we reserve the privilege of adapting all such legitimate changes in the form, construction and relative arrangement of the several parts as may be fairly embodied within the spirit and scope of the invention as claimed.

We claim:

1. In combination with a propulsion unit for a load bearing axle, means for entraining said unit with the axle including a shiftable power transmitting element adapted to engage a driven element, and means responsive to the influence of the energizing medium for the propulsion unit operatively connected to said power transmitting element and constructed and arranged to control the supply of the energizing medium to

the propulsion unit and initiate the operation of the latter at low speed whereby the power transmitting element is slowly rotated prior to its full effective entrainment with the driven element. 65

2. In combination with a pressure fluid actuated propulsion unit for a vehicle driving axle, means for entraining said unit with the driving axle including a power transmission element movable in a planetary path and in constant gear with the propulsion unit, and means influenced by the pressure fluid and connected to said power transmission element, constructed and arranged to control the supply of pressure fluid to said unit and initiate the operation thereof at 70 slow speed to thereby rotate the power transmission element on its axis and simultaneously shift said element in its planetary path to its full entrained position with relation to the driving axle. 75

3. In combination with a propulsion unit for a vehicle, driving axle and fluid pressure supply means therefor, means for entraining said unit with the driving axle including a power transmitting gear in constant gear with the propulsion unit and movable in a planetary path, and means operatively connected to said power transmitting gear and interposed in the pressure fluid supply connection for the propulsion unit 80 influenced by the pressure fluid and controlling its supply to the propulsion unit to initiate the operation of the latter at low speed and thereby rotate the power transmitting gear on its axis during its planetary movement to its full entrained position with relation to the vehicle driving axle. 85

4. In combination with a propulsion unit for a vehicle axle and a driving shaft for said axle operatively connected to the propulsion unit, a fluid pressure supply connection for the propulsion unit, and means for entraining said shaft with the vehicle axle, including a power transmitting element supported upon said shaft for planetary movement and constantly geared to the shaft, and a valve interposed in the pressure fluid supply connection for the propulsion unit operatively connected to said power transmitting element and responsive to the pressure influence of the fluid to impart a planetary movement to the power transmitting element and move the same to its entrained position with relation to the vehicle axle. 100

5. In combination with a propulsion unit 110 for a vehicle axle, a pressure fluid supply connection for said unit and a driving shaft operatively connected to the propulsion unit: a bearing oscillatably mounted on said shaft, a driving gear fixed to the shaft, a 115 driven gear on the axle, a power transmitting gear rotatably mounted in said bearing and constantly engaged with the gear on said

shaft, and a pressure responsive valve interposed in the supply connection to the propulsion unit and operatively connected to said bearing, said valve being 5 constructed and arranged to control the passage of the pressure fluid and initiate operation of the propulsion unit at low speed simultaneously with the planetary movement of the power transmission gear 10 towards its entrained position, whereby said

gear is rotated on its own axis, and thereby finally producing full entrainment of said gear with the driven gear of the axle simultaneously with the full speed operation of the propulsion unit.

15

In testimony that we claim the foregoing as our invention, we have signed our names hereunder.
